APPARATUS FOR USE IN TREATING HIDES,
SKINS, AND THE LIKE

Joseph L. Russell, Peabody, Mass., assignor, by
mesne assignments, of one-half to Rose E. Rus-
sell, Peabody, Mass., and one-half to Donald
R. Pope, Danvers, Mass.

Application July 20, 1939, Serial No. 285,535

9 Claims. (Cl. 149—8)

My invention relates to apparatus for use in the treatment of hides, skins and the like during the process of manufacturing leather, and it has for its object to provide an improved apparatus of the class described by means of which various operations such as drying, pickling, coloring, tanning and washing may be expeditiously, efficiently and economically performed.

To these ends I have provided an improved apparatus of the class described which may be constructed and operated as set forth in the following description, the several novel features of the invention being pointed out and defined in the claims at the close thereof.

In the accompanying drawings—

Figure 1 is an elevation of one form of apparatus constructed in accordance with this invention.

Figure 2 is a section on line 2—2 of Fig. 1.

Figure 3 illustrates one method of loading and 20 unloading the drum of the apparatus illustrated in Figs. 1 and 2.

Figure 4 illustrates an alternative form of apparatus constructed in accordance with this invention.

Figure 5 is a detail hereinafter described.

The embodiment of my invention illustrated in Figs. 1 and 2 comprises a stationary and fixed framework including a base 10, uprights 11, 11 at opposite ends thereof, a top cross-bar 12, and a lower cross-bar 13 disposed a short distance above the base 10.

Journalized in bearings 14 and 15, provided on the cross-bar 13 and base 10, respectively, is a vertical shaft 16 and to the upper end portion of this shaft is fixed the lower end of a rectangular frame 17. The upper end of this frame 17 is fixed to one end of a vertical trunnion or shaft section 18 which is axially aligned with the shaft 16 and rotatably mounted within a bearing 19 provided at the middle of the top cross-bar 12. It will thus be clear that the frame 17 is mounted to rotate on a vertical axis coincident with the axes of shaft 16 and trunnion 18.

The oppositely disposed vertical side bars of frame 17 are made with sockets 20 within which the opposite end portions of a horizontal shaft 21 are fixed with provision for removal by pins 22 as shown in Fig. 1. The axis of the fixed shaft 21 intersects the vertical axis on which the frame 17 rotates.

Journalized in bearings provided upon the inner sides of the two oppositely disposed side bars of frame 17 are two vertically disposed shafts 23, each provided at its upper end with a beveled

pinion 24 meshing with the beveled gear 25 fixed to the proximate end of a drum 26 that is rotatably mounted upon the fixed shaft 21. This drum 26 is preferably of cylindroidal or cylindrical form. At its lower end the vertical shafts 23 are connected by miter gears 24 with the opposite ends of the armature shaft 27 of an electric motor 28. The axes of shafts 27, 23, 21 and 16 and trunnion 18 are all disposed in one vertical plane.

The center of gravity of the motor 28 is coincident with the vertical axis on which the frame 17 rotates and all of the parts of frame 17 and the parts which are carried by the latter, are 15 symmetrically disposed so that the weight of said parts at one side of said vertical axis is the same, or approximately the same, as the weight of the parts at the opposite side of said axis. This avoids gyroscopic effect while the frame 17 is rotated.

The shaft 16 of frame 17 is connected through beveled gears 29 with a driving shaft 30 to which power is supplied from any suitable source so that it may be varied as desired.

25 Fixed to the top cross-bar of frame 17 is a horizontal plate or annulus 31 of insulating material to the top side of which are fixed two concentric metal commutator rings 33 and 34 which are engaged, respectively, by spring contacts 36 and 37 mounted upon the under side of the top cross-bar 12. The contacts 36 and 37 are connected by wires 38 and 39 with a rheostat R which in turn is connected through a cable 40 with a source of current.

35 Wires 41 and 42 connect the commutator rings 33 and 34, respectively, with the terminals of motor 28 and these wires are incorporated in a cable 43 which is fastened to frame 17.

It will be clear that when the control lever of 40 rheostat R is swung toward the left, Fig. 1, the wires 38 and 39 are connected with the source of current and the latter is supplied through contacts 36 and 37, rings 33 and 34 and wires 41 and 42 to the motor 28 whose armature shaft acts through the connections described to rotate the drum 26 on the fixed shaft 21. As will be clear the speed of rotation of drum 26 may be varied as desired by means of the rheostat. It will also be clear that shaft 30 may be driven at any desired speed. The described construction also has the advantage that the drives for drum 26 and frame 17 are independent and either may be rotated to the exclusion of the other.

As shown in Figs. 1 and 2 the cylindrical wall 45 of drum 26 is made with a longitudinal slot

within which is fixed one end of a web 48 of cloth, burlap or the like. The end of the web 48 which is within the drum 26 is formed with a transverse pocket 46 within which is disposed a metal rod 47, said rod providing an enlargement or bead which is of greater thickness than the width of slot 45 so that the web is securely anchored to the drum.

In preparing the apparatus for operation the web 48 is wound on to drum 26 and as it is wound thereon the skins, hides or other pieces of sheet material that are to be treated, are introduced between the convolutions of the web as shown at 49 in Fig. 2. Thus the finished wrapping on the drum 26 consists of alternating layers of web and skins, hides or the like. When the web is completely wound on to the drum a plurality of straps 50 are applied to the exterior thereof after which shaft 30 and motor 28 are started in operation with the result that frame 17 is rapidly rotated on a vertical axis while the drum 26 is rapidly rotated on a horizontal axis.

When the machine is used for drying skins, hides and the like, and both shaft 30 and motor 28 are in operation, the centrifugal force exerted upon the convolutions of the web and the pieces of material between said convolutions serves to flatten out and smooth said pieces as well as to force moisture radially outward away from the rotating drum. At the same time the rotation of the frame 17 on the vertical axis imposes centrifugal force upon the moisture within the wrapping on the drum and forces the same toward the opposite ends of the latter where it is discharged. It follows, therefore, that after a comparatively short period of time the skins, hides or the like may be removed from the machine in a dry, smooth, stretched and unrinkled condition.

When it is desired to subject the skins, hides or the like to the action of a liquor while being treated in the machine shown in Figs. 1 and 2 I may employ a loading device such as that illustrated in Fig. 3. This loading device comprises a vat 51 provided with a removable top 52 and within this vat may be introduced a body of liquor 53 for either pickling, tanning, washing, coloring or the like within which the outer end portion of the web is stowed as shown. From the drum 26 the web 48 extends around a guide pulley 54 and thence downwardly into the vat 51 where it is submerged in the liquor 53. The drum 26 is then rotated manually or otherwise in the direction of the arrow and as the web is wound thereon the skins or hides 49 placed successively on the table 52 are shoved into position between the convolutions of the web. Thereafter the straps 50 are applied and the loading device 51 removed leaving the machine, shown in Figs. 1 and 2, free to be operated. During the operation of the machine centrifugal force distributes the liquor with which the web is saturated so that the skins, hides or the like are uniformly treated by the same and also stretched and smoothed out.

The vat 51 is provided with an off-take pipe 55 controlled by a normally closed valve 56 so that the liquor contents of the vat may be withdrawn when desired so that the loading device may be used without the liquor 53.

When it is desired to emboss the skins, hides or the like, which are operated upon by the machine shown in Figs. 1 and 2, I may introduce metallic embossing elements 57, Fig. 5, between the skin, hide or the like 49 and the web 48.

These metallic embossing elements may consist of pieces of wire netting or the like which are flexible so that they will assume the curvature of the convolutions of the web. As will be clear, rotation of the drum on the axis of shaft 21 imposes centrifugal force upon the web and the work held thereby so that the design of the embossing element is imposed upon the work.

In Fig. 4 of the drawings I have illustrated an alternative construction which comprises a vat 58 through which extends a fixed shaft 59. On this shaft is rotatably mounted the drum 26a provided, as in Figs. 1 and 2, with a fabric web 48 and straps 50. As shown in Fig. 4 the drum 26a is provided at one end with a beveled gear 60 driven by a beveled gear 61 fast on a shaft 62 journaled in bearings provided within vat 58. Shaft 62 extends through one wall of the vat and is belt-driven as shown. A removable closure wall 63 is provided for the top of the vat. In using this form of apparatus a body of liquor 64 is introduced into the vat and after applying the closure 63 the drum is started in operation. The liquid contents of vat 58 may be fat liquor or liquor for pickling, tanning, washing or coloring the work and, as will be clear, several of these operations may be carried out in succession without removal of the work from the drum 26a. When changing from one of these operations to another the liquor 64 may be exhausted through a draw-off pipe 65 that is normally closed by a valve 66 and another liquor substituted therefor which is appropriate for the next operation.

In carrying out the two-bath process of chrome tanning I may subject the skins to the first chromic acid bath as heretofore and thereafter transfer the skins to the apparatus illustrated in Figs. 1 and 2 saturating the cloth web with the second reducing bath liquor by means of the loading device shown in Fig. 3.

Sometimes the skins are tanned by a one-bath chrome tanning operation in which case the apparatus of Figs. 1 and 2 would be used with the fabric web saturated with the tanning solution. In some cases both steps of the two-bath chrome tanning operation can be carried out by using the loading devices shown in Fig. 3.

It is also possible to carry out many other tanning operations utilizing the apparatus herein illustrated and described.

When incorporated within the winding on the drum each skin or hide is in full extended condition and under full control, and while so incorporated it can be de-greased, tanned, washed, colored and fat liquored. Also it may be set back and dried over to soften for coat or glove leather. In its operation the machine stretches the hides or skins and softens them so that there is no shrinkage. A distinct advantage to the above described apparatus and method of treatment is that tacking, stripping and trimming heretofore required are dispensed with which accomplishes considerable saving and reduces expense.

In the embodiment of the invention illustrated in Figs. 1 and 2 the axis of rotation of the drum intersects the center of gravity of the latter as does also the axis of rotation of the frame 17.

70 What I claim is:

1. An apparatus of the character described comprising a cylindrical drum around the exterior of which the skins, hides or the like are wrapped; means carried by said drum for holding the skins, hides or the like in position thereon; a frame on

which said drum is mounted to rotate on its own axis; means supporting said frame for rotary movement on another axis perpendicular to the axis of said drum and intersecting the same midway between the opposite ends of the drum; means for rotating said drum on its axis, and means for rotating said frame on its axis of rotation.

2. An apparatus of the character described comprising a drum around the exterior of which the skins, hides or the like are wrapped; means carried by said drum for holding the skins, hides or the like in position thereon; a frame on which said drum is mounted to rotate on an axis intersecting its center of gravity; means supporting said frame for rotary movement on another axis perpendicular to said first mentioned axis and also intersecting the center of gravity of said drum; means for rotating said drum on said first mentioned axis, and means for rotating said frame on its axis of rotation.

3. An apparatus of the character described comprising a drum; a fabric web of sufficient length to be wrapped around said drum to the extent of a plurality of convolutions with skins, hides or the like, alternating with said convolutions, the inner end of said web being fastened to said drum; flexible embossing elements of sheet material incorporated within the convolutions of said web alongside of said skins, hides or the like; means for holding said web, said skins, hides or the like, and said embossing elements in position on said drum; a frame on which said drum is mounted to rotate on an axis intersecting its center of gravity; means supporting said frame for rotary movement on another axis perpendicular to said first-mentioned axis and also intersecting the center of gravity of said drum; means for rotating said drum on said first-mentioned axis, and means for rotating said frame on its axis of rotation.

4. An apparatus of the character described comprising a drum; a fabric web of sufficient length to be wrapped around said drum to the extent of a plurality of convolutions with skins, hides or the like, alternating with said convolutions, the inner end of said web being fastened to said drum; means carried by said drum for holding said web and said skins, hides or the like, in position on said drum; a frame on which said drum is mounted to rotate on an axis intersecting its center of gravity; a support on which said frame is mounted to rotate on an axis at right angles to said first mentioned axis and also intersecting said center of gravity; an electric motor mounted on said frame; mechanism through which said motor drives said drum; electrical connections through which said motor is supplied with current, said electrical connections including a commutator whereof parts are mounted on said frame and parts are mounted on said support, and means, independent of said motor, for rotating said frame.

5. The combination with an apparatus of the

character described comprising a drum supported for rotation on a horizontal axis; a fabric web of sufficient length to be wrapped around said drum to the extent of a plurality of convolutions with skins, hides or the like, alternating with said convolutions, the inner end of said web being fastened to said drum, and means for fastening the outer end of said web in position against the exterior of said wrapping, of a loading device consisting of a movably supported vat adapted to receive most of said web when it is unwrapped from said drum and also adapted to hold a liquid, and means adjacent to the top of said vat for supporting each skin, hide or the like, so that it will be wound on to said drum with said web when said drum is rotated in a direction to wind said web thereon preparatory to operation of the apparatus.

6. An apparatus of the character described comprising a work-holding member on which the skins, hides or the like are mounted; means carried by said member for holding the skins, hides or the like in position thereon; a frame on which said member is mounted to rotate on one axis which intersects its center of gravity; a support for said frame on which the latter is mounted to rotate on an axis at right angles to said first-mentioned axis and intersecting said center of gravity, means for rotating said member on its axis and means for rotating said frame on its axis.

7. An apparatus of the character described comprising a work-holding member around the exterior of which the skins, hides or the like are wrapped; means carried by said member for holding the skins, hides or the like in position thereon; a frame on which said member is mounted to rotate on one axis which intersects its center of gravity; a support for said frame on which the latter is mounted to rotate on an axis at right angles to said first-mentioned axis and intersecting said center of gravity; means for rotating said frame on its axis of rotation, and independent means for rotating said member on its axis of rotation.

8. An apparatus constructed in accordance with claim 7 and wherein said last-mentioned means includes an electric motor mounted on said frame, a current supplying circuit, and a commutator in said circuit whereof a part is mounted on said frame and connected with said motor and whereof a part is mounted on said support and connected with a source of current.

9. An apparatus constructed in accordance with claim 7 and wherein said last-mentioned means includes an electric motor mounted on said frame with its center of gravity coincident with the axis of rotation of the latter, a current supplying circuit, and a commutator in said circuit whereof a part is mounted on said frame and connected with said motor and whereof a part is mounted on said support and connected with a source of current.

JOSEPH L. RUSSELL.
